Primary Examiner — Randall H Gholson(57) **CLAIM**

The ornamental design for an open end wrench, as shown and described.

DESCRIPTION

FIG. 1 is a left perspective view of an open end wrench showing our new design;

FIG. 2 is a right perspective view thereof;

FIG. 3 is a front plan view thereof;

FIG. 4 is a rear-plan view thereof;

FIG. 5 is a detailed left perspective view of the engagement features taken in FIG. 1 thereof;

FIG. 6 is a detailed right perspective view of the engagement features taken in FIG. 2 thereof;

FIG. 7 is a detailed front perspective view of the engagement features taken in FIG. 3 thereof; and,

FIG. 8 is a top plan view thereof.

The broken line showing the tool body in FIGS. 1–8 are included for the purpose of showing environmental structure and form no part of the claimed design.
